Patented March 8, 1904.

UNITED STATES PATENT OFFICE.

MAX TONNEMANN, OF JERSEY CITY, NEW JERSEY.

DESIGN FOR A SOUVENIR-PLATE.

SPECIFICATION forming part of Design No. 36,843, dated March 8, 1904.

Application filed February 6, 1904. Serial No. 192,474. Term of patent 14 years.

To all whom it may concern:

Be it known that I, MAX TONNEMANN, a citizen of the United States, residing in Jersey City, in the county of Hudson and State of New Jersey, have invented a new, original, and ornamental Design for Souvenir-Plates, of which the following is a specification.

The nature of my design is fully represented in the accompanying drawing, to which reference is made and which shows in elevation to a plate embodying my design.

I claim as my invention—

The ornamental design for a souvenir-plate, as shown.

MAX TONNEMANN.
